UNITED STATES PATENT OFFICE.

THOMAS BEARMAN, OF OWEN SOUND, CANADA.

LUMBER CIRCULAR-SAW MACHINE.

SPECIFICATION forming part of Letters Patent No. 614,924, dated November 29, 1898.

Application filed December 27, 1897. Serial No. 663,576. (No model.)

To all whom it may concern:

Be it known that I, THOMAS BEARMAN, manufacturer, of the town of Owen Sound, in the county of Grey, in the Province of Ontario, Canada, have invented certain new and useful Improvements in Lumber Circular-Saw Machines, of which the following is a specification.

My invention relates to improvements in lumber circular-saw machines more particularly adapted for the sawing of logs; and the object of the invention is to design a simple, compact, economical, and efficient form of machine by which a thin small saw may be utilized for the sawing of logs in various ways and a great saving in timber and power thereby effected; and it consists, essentially, of a suitable stationary frame provided with a swinging frame, at the front of which the saw is held flush on the end of cross-shaft, which derives motion from a belt from the main driving-shaft, the swinging frame being adjusted, preferably, by means of screw-spindles deriving movement through a bevel-gear and shaft and belt from the main shaft and the log being turned and fed and the parts otherwise constructed and arranged in detail, as hereinafter more particularly explained.

Figure 1 is a perspective view of my improved circular-saw machine. Fig. 2 is an enlarged detail of the saw and adjacent cutter and means for adjusting same. Fig. 3 is an enlarged sectional perspective detail of the joint at the top of the screw-spindles. Fig. 4 is a detail of the trunnions through which the screw-spindles pass. Fig. 5 is a detail of the hollow trunnions upon which the swinging frame is pivoted. Figs. 6, 7, 8, 9, 10, 11, and 12 are end views of logs, showing the various cuts which may be accomplished by my circular-saw machine.

In the drawings like letters and numerals of reference indicate corresponding parts in each figure.

45 A A are the side bars of the frame. A' is the end bar.

B B are the vertical standards, and C is the cross-bar at the top of the vertical standards.

A² is a cross-bar extending between the side bars A.

A³ is a bar extending from the cross-bar A² to the end bar A'.

D is the main driving-shaft, which is supported on suitable bearings d in the side bars A A.

55

E E are hollow trunnions located at each end of the shaft D and through which such shaft partially extends, such hollow trunnions E E being secured to the side bars A by suitable bolts and being concentric to the shaft D. The trunnions E are provided with side flanges e.

F F are side bars of the swinging frame, which are pivoted on the trunnions E E.

F' is a cross-bar connecting the swinging 65 side bars F.

G G are trunnions secured to the outer ends of the side bars F F and to the inside of the bars and formed similarly to the trunnions E E.

70

H is a supplemental swinging frame provided with side bars H' and an extended end bar H², which is provided with a jaw h, the members of which extend to each side of the saw I, so as to steady it, the saw being shown 75 in dotted lines in Fig. 1.

J is the saw-shaft, which is suitably supported in journals j on the end of the side bars F of the swinging frame, such shaft extending through the hollow trunnions G. The 80 end of one side bar H' of the supplemental frame H is provided with a handle h' and has a spring-plunger connected to such side bar which is designed to be brought into engagement with one or other of the notches of the 85 quadrant g, attached to the end of the side bar, so as to adjust the supplemental frame H to any desired level, whereby the jaws h may be brought into proper central position near the cutting edge of the saw.

90

K is a pulley (shown mostly in dotted lines) secured to the shaft J.

L is a pulley secured to the main shaft. The pulleys K and L are connected together by a belt l.

95

M is an open frame pivoted on the studs m, journaled in the bearing-brackets m'.

N and N' are spindles journaled in suitable bearings in the sides of the frame M, and n and n' are pulleys which are suitably held in 100 frictional contact with each other.

n² is a pulley journaled on the shaft N, adjacent to the pulley n.

O are screw-spindles, one only of which is

shown, extending and screwed through the trunnions o , pivotally held in bearing-brackets O' , secured on the side bars F of the swinging frame. The bearing-brackets O' are provided with slots o' , so as to allow of a limited swinging movement of the screw-spindles O . The side bars F are also slotted for this purpose.

5 P are ways, preferably of metal in arc-shape form, secured to the side of the standards B B , one only being shown, but the other is at the opposite side of the far standard. P' are bearing-blocks which rub against such ways and hold the swinging frame from lateral 15 vibration.

10 The upper ends of the screw-spindles O are provided with bevel-pinions O^2 , which are suitably secured onto the spindles and balls o^2 , which have bearings in sockets Q , formed at 15 the center of the top of the bearing-brackets Q' , as indicated.

15 R is a counter-shaft supported in suitable bearings r , secured in the top of the cross-bar C and provided at the end with bevel-pinions R' , which mesh with the bevel-pinions O^2 at the upper end of the screw-spindles O . As the pulley and socket at the top of the spindles O are directly in line with the center of the shaft R , it will be readily seen 20 that the bevel gear-pinions O^2 and R' will mesh perfectly with each other no matter in what position the screw-spindles O may be 25 swung.

30 S is a pulley secured on the rod R , connected by a belt s to the pulley n^2 on the spindle N .

35 T is a lever pivoted on the quadrant-frame t , designed to mesh with one of the three notches t' of the quadrant. The quadrant-frame T is secured at the base by suitable 40 bolts to the flooring or frame of the building in proximity to the supplemental swinging frame H . The lower end of the lever T is pivotally connected to a rod T' , which is connected at the opposite end to the lower end 45 of the frame M .

50 U is a pulley secured on the main driving-shaft D opposite the pulleys n and n' . In the position in which the lever T is shown in the drawings—that is, in the front notch of the quadrant t —the pulley N is brought in frictional contact with the pulley U on the main shaft. By throwing the lever T opposite the second notch both pulleys n and n' are disconnected from the shaft. By bringing the 55 lever T opposite the nearest notch shown in the drawings the lower pulley n' is thrown against the pulley U . Now as the pulley U is located on the driving-shaft it will be seen that if the pulley n is against the pulley U the driving-shaft, revolving in the direction indicated by arrow, will impart motion to the pulley n and n^2 , causing the belt S to move in the direction indicated by arrow and communicating motion to the bevel-pinion O^2 in the direction indicated by arrow, thereby raising the swinging frame on account of the screw-spindles O being caused to move downwardly through the 60

trunnions o . When the pulley n' is brought against the pulley U on the main shaft, such pulley n' will cause the pulley n to rotate in 70 the opposite direction, and consequently drive the pulley S in the opposite direction, and consequently the spindles O , thereby causing the screw-spindles to pass upwardly through the trunnions o , and consequently 75 lowering the swinging frame. It will thus be seen that by manipulating the lever T the swinging frame may be raised and lowered to any desired position, and thereby bring the saw either above or below the log 2 , which is 80 held on a carriage 3 , longitudinally movable on a track 4 . By throwing out both friction-pulleys n and n' the swinging frame will of course remain stationary and hold the saw 85 so. The supplemental frame H may be also 90 adjusted so as to bring it level, and consequently the jaws h , substantially on a line with the horizontal plane of the saw when cutting.

90 The log 2 is held in lathe-points 5 , supported in the brackets 6 on the carriage. A quadrant 7 is also provided with equidistant notches, with which a lever 8 is designed to 95 coact, such lever being removably secured on the square end of the lathe-point and provided with a spring-plunger 9 , designed to be brought into engagement with the notches in the quadrant. By adjusting the lever in relation to the quadrant the log is simultaneously turned and held in any desired 100 position for the various ways of sawing logs, such as indicated in Figs. 6 to 12, in which Fig. 6 shows, diagrammatically, the saw in position for trimming the log. Fig. 7 shows the position the saw assumes to cut clap- 105 boards; Fig. 8, an octagonal cut; Fig. 9, a cut into the center of a large log, the saw being intended to be raised into the upper position and lower position to effect the cutting of the lumber in this manner; Fig. 10, a quarter-cut; Fig. 11, sawing the log into boards 110 by giving four turns to the log and by sawing from above or below, and Fig. 12 another alternative form.

115 In turning the log around of course the lever 9 would have to be moved from the square end of the lathe-point, so as to completely turn the log.

120 In Fig. 2 I show the saw supported on the end of the disk 10 , to which it is bolted by countersunk bolts, the outside of the saw being flush. Suitable cutters 11 are provided in proximity to the saw secured in position within notches in collars 12 , which are located 125 on the hub 13 and through which the key 14 extends. The collar 15 is provided with a circumferential groove, such collar being secured to the cutter-collars. 16 is a lever pivoted at 17 and having a pin 18 extending into a groove in the collar 15 . By swinging the 130 lever the cutters may be moved longitudinally on the hub out of position, so they will not operate. Ordinarily these cutters are used to trim the rough outside edge of the log.

From this description it will be seen that I am enabled to use in a machine such as I describe a very small and thin saw and to cut small or large logs, whether rough or smooth, in various ways. Formerly such logs were cut by very large thick saws, and consequently a great deal of the lumber was wasted in sawdust. By my machine this is entirely avoided. It will also be understood that on account of using the small saw I can effect a great saving of power. On account of the compactness of my machine it may be also readily moved from place to place.

What I claim as my invention is—

1. In combination, the main frame, the swinging frame, the main drive-shaft, the saw, the standards, the cross-piece supported thereby, the supplemental shaft supported thereby driven from the main drive-shaft, a bevel-gear fixed to the supplemental shaft, a bracket extending transversely of said cross-piece having a socket in line with the end of the supplemental shaft, a screw-spindle having a bulbous head held in said socket, a gear carried thereby meshing with the first gear and a pivotal screw connection between said screw-spindle and said swinging frame, substantially as described.

2. In a lumber-sawing machine, in combination a suitable frame, a swinging frame, a saw located at the outer end thereof on the end of a suitable shaft, suitable uprights supported on the frame suitable bearings on the side bars of the swinging frame slots in the bearings, screw-spindles screwed through the trunnions bevel-pinions at the upper ends of the screw-spindles, a ball-and-socket bearing for the upper end of the screw-spindles, a counter-shaft provided with bevel-pinions meshing with the bevel-pinions at the upper end of the screw-spindles, the pulley on the counter-shaft, the pulley on the main shaft, the minor swinging frame having two spindles with abutting friction-pulleys, a supplemental pulley on one of the spindles of the abutting friction-pulleys and a belt connecting such supplemental pulley to the pulley on the counter-shaft as and for the purpose specified.

3. The combination with the stationary frame and swinging frame the shaft support-

ed in suitable bearings on the end of the swinging frame, the saw secured on the end of the shaft, the hollow trunnions secured to the inside of the side bars of the swinging frame and through which the saw-shaft extends, the supplemental frame having the side bars pivotally swung on the outside of the hollow trunnions through which the saw-shaft extends, the end extension-bar of the supplemental frame provided with jaws, the handle end of one of the side bars of the frame, the quadrant on the side bars of the swinging frame in proximity to the saw-shaft and the spring-pressed plunger coacting therewith and operated from the handle on the end of the side bar as and for the purpose specified.

4. In combination the main frame, the uprights, the screw-spindle extending through the side bars of the swinging frame, the bevel-pinions, the counter-shaft, pulley on the counter-shaft, the pivotally-supported pulley-frame provided with abutting friction-pulleys journaled on the spindles, the supplemental pulley on the same spindle as one of the friction-pulleys, the pulley connecting the supplemental pulley to the pulley on the counter-shaft, the main shaft and friction-pulley thereon, the rod connected to the lower end of the pivotally-supported pulley-frame, the lever connected to the forward end of the rod in proximity to the supplemental swinging frame and an independent notched quadrant-frame suitably supported and on which such lever is pivoted and with which it is designed to coact as and for the purpose specified.

5. In a lumber-sawing machine, the combination with the saw secured on the end of the saw-shaft with the outer face flush, of the cutters on the inside of the saw held in position by suitable collars, a grooved collar to the outside having longitudinal movement on a key, a lever and pin extending into the groove on the collar for throwing the cutters laterally upon the shaft as and for the purpose specified.
